UNITED STATES PATENT OFFICE.

FRANCIS ADIX, OF BOONE, IOWA.

HARROW.

No. 839,799.

Specification of Letters Patent.

Patented Jan. 1, 1907.

Application filed July 3, 1906. Serial No. 324,691.

To all whom it may concern:

Be it known that I, FRANCIS ADIX, a citizen of the United States, residing at Boone, in the county of Boone and State of Iowa, have invented certain new and useful Improvements in Harrows, of which the following is a specification, reference being had therein to the accompanying drawings:

My invention relates to improvements in harrows, and more particularly to tooth structures therefor; and it consists in the novel construction, combination, and arrangement of parts hereinafter described and claimed.

The object of the invention is to improve and simplify the construction of devices of this character, and thereby render the same more durable and efficient.

The above and other objects which will appear as the nature of the invention is better understood are accomplished by the construction illustrated in the accompanying drawings, in which—

Figure 1 is a top plan view of my improved harrow. Fig. 2 is a vertical sectional view taken on the plane indicated by the line $x-x$ in Fig. 1. Fig. 3 is a detail vertical sectional view taken on the plane indicated by the line $y-y$ in Fig. 2. Fig. 4 is a detail horizontal sectional view through the coupling or hinge devices connecting the tooth-bars of two sections of the harrow, the plane of the section being indicated by the line 4-4 in Fig. 3; and Fig. 5 is a detail perspective view of one of the tooth-bars, one of the connecting-bars, and one of the runners for supporting the intermediate section of the harrow when the latter is not in use.

My improved harrow consists, preferably, of three similar sections 1 2 3, arranged side by side and hingedly connected, so that the two end or outside sections 2 3 may be folded together above the intermediate or middle section 1 when the device is not in use for harrowing. Since these harrow-sections are substantially alike, a description of one will suffice for all. Each section consists, preferably, of five transverse tooth-carrying bars or rods 4, mounted for rotation in three longitudinal connecting channel bars or beams 5. The latter are connected together and spaced apart by diagonal braces 6 in the form of metal straps having their angularly-bent

ends bolted to the connecting-bars. The tooth-bars 4 are in the form of metal tubes or 55 sections of gas-pipe and project through transversely-aligning openings in the connecting-bars 5, in which they rotate. They are prevented from slipping endwise in the bars 5 by split pins or keys 7, passed through 60 openings in the bars 4 on opposite sides of the bars 5. Washers 8 are interposed between said keys and the channeled sides of the bars 5, as shown. In some instances the washers 8 and pins 7 are omitted, other parts taking 65 their places, as hereinafter described and as will be seen upon reference to the drawings.

Any number of harrow-teeth of any suitable form may be arranged on each of the bars 4; but I preferably employ spike-teeth 9 70 and arrange them at suitable intervals along said bars. These teeth have the lower ends of their square bodies pointed, and their upper ends are formed with reduced stems or shanks 10, which extend through openings in 75 the bars 4 and are screw-threaded to receive nuts 11. In order to adjust the teeth angularly and hold them adjusted, I provide on each of the bars 4 adjacent to its center an arm 12. These arms have their inner ends 80 shaped to fit said bars and are secured thereon by transverse pins 13, and their outer ends are pivotally connected to a connecting rod or link 14, which extends longitudinally and has its rear end pivoted to a hand-lever 15. 85 The latter takes the place of the arm 12 on the rearmost bar 4 and has its lower end shaped to fit said bar and secured thereon by a pin 16. The upper end of the lever 15 is formed with a handle and has pivoted upon 90 it a hand-piece 17, which operates a spring-seated pawl 18, slidably mounted on the lever and adapted to engage a segmental rack 19, provided on the central connecting-bar 5, as clearly shown in Fig. 2. 95

In order to permit the harrow to be readily moved from one field to another without the use of a sled, wagon, or the like, I provide on the middle section 1 runners 20. These runners are preferably carried by the front and rear tooth-bars 4 and are so disposed that they are elevated above the ground when the teeth are engaged therewith and are lowered to engage the ground when the hand-lever is swung to elevate the teeth. Each of 105 the runners 20 is in the form of a curved or

cam-shaped arm formed at one end with a portion 21, shaped to fit over one end of one of said bars 4, on which it is retained by a transverse or cross pin 22. When the harrow is supported on the runners 20, its two end sections 23 are swung upwardly together above the section 1 and may be retained in this folded position by a small chain or any other mean.

10 The folding of the harrow-sections 23 is permitted by the hinge connections 23, provided between the adjacent ends of the front and rear tooth-bars 4 of each section. Each of the hinge connections 23 consists of a hook member 24 and an eye or loop member 25, the former being adapted to detachably engage the latter. Each of the hook members 24 is formed with a reduced end or shank 26, adapted to fit into the inner end of one of 15 said bars 4 of one of the end sections and to be secured therein by the shank 10 of one of the teeth 9. Each of the eye members 25 is formed with a similar end 27, adapted to fit into one end of one of the said bars 4 of the 20 middle section 1 and to be secured therein by the pin 22, which attaches the adjacent runner 20 to such bar 4, as clearly shown in Figs. 3, 4 of the drawings. On the front of the two outer connecting-bars 5 of each section is secured 25 an apertured plate 29. The plates 29 on each section are connected by twisted clevises or clips 30 to one of the three members of a sectional draft-bar 31. The three members or sections of this draft-bar are connected by hinges 32, which have their pins 33 in longitudinal alignment with the hinge connections 23, so that the draft-bar folds with the harrow-sections 23. The middle member of the bar 31 is connected by links 33 to rings 34, which are in turn connected by links 35 to a ring 36, to which latter the draft animal or animals are attached. Each of the end members of the draft-bar 31 is connected by long and short links 37, 38 to a 40 ring 39, which is in turn connected by a short link 40 to one of the rings 34, as will be seen upon reference to Fig. 1. It will be observed that when the harrow-sections are open or in the position shown in said figure the pull or 45 draft will be distributed equally on the three sections of the harrow by reason of the said link connections and that when the harrow-sections are folded the draft will be entirely upon the middle section 1. In either position there is no strain whatever upon the 50 hinge connections.

The operator sits upon a seat 45, mounted upon a riding attachment 42, comprising a wheel-supported frame 46, having forwardly-diverging bars 41, which are secured at their front ends to the central section 31 of the draft-bar. This riding attachment forms the subject-matter of a separate application,

Serial No. 334,447, filed September 13, 1906, and need not be described in detail. 65

The construction, operation, and advantages of the invention will be readily understood from the foregoing description, taken in connection with the accompanying drawings. It will be seen that the device is of simple, 70 strong, durable, and comparatively inexpensive construction, that it is convenient and easy to handle, and that it is very effective in operation. One or both of the outside sections may be folded without removing the 75 riding attachment and without interfering with the driver thereon. By hooking the sections together, then folding them, and lowering the runners 20 the device may be pulled over any road or field or through any 80 gate. It will be seen that by adjusting the hand-levers 15 the teeth of the harrow-sections may be set at any desired angle or may be thrown upwardly out of operation and the runners 20 on the central section simultaneously lowered to engage the ground. The hinge connections 23 are disconnected when it is desired to adjust the tooth-bars of the several sections of the harrow. 85

Various changes in the form, proportion, 90 and the minor details of construction may be resorted to without departing from the spirit or sacrificing any of the advantages of the invention as defined by the appended claims. 95

Having thus described my said invention, what I claim as new, and desire to secure by Letters Patent of the United States, is—

1. A harrow comprising a frame, cylindrical tooth-carrying bars rotatable therein, 100 runners having cylindrical portions formed with transverse openings to fit certain of said cylindrical tooth-carrying bars, said runners also having cam-shaped arms formed integral with said cylindrical portion and projecting laterally therefrom, cross-pins passed through the cylindrical portions of said runners and said bars for retaining the former upon the latter, and means for operating said bars to simultaneously elevate the teeth 110 thereon and lower the runners, the latter having their cam-shaped arms disposed longitudinally with respect to the direction of movement of the harrow, substantially as shown and described. 115

2. A harrow comprising longitudinal channel-metal connecting-bars, braces connecting said bars, transverse bars rotatable in said channel-bars, teeth upon said transverse bars, cross-pins in said transverse bars on opposite sides of said channel-bars, washers on said transverse bars between said cross-pins and the channel-faces of said channel-bars, and means for adjusting said transverse bars in said channel-bars. 120

3. A harrow comprising longitudinal chan-

nel-metal connecting-bars, diagonal braces connecting said bars, transverse tubular bars rotatable in said channel-bars, teeth upon said tubular bars, split pins in said tubular bars on opposite sides of said channel-bars, washers on said tubular bars between said pins and the channel-faces of said channel-bars, arms upon said tubular bars, a rod connecting said arms, a hand-lever for operating

10
said rod, a pawl and rack for locking said lever, and a draft connection at the front ends of said channel-bars.

In testimony whereof I hereunto affix my signature in presence of two witnesses.

FRANCIS ADIX.
